INVENTOR

Charles F. Nickerson,
By his Atty.
Sperry, C. F. Nickerson

UNITED STATES PATENT OFFICE.

CHARLES F. NICKERSON, OF READING, MASSACHUSETTS.

VENTILATOR.

SPECIFICATION forming part of Letters Patent No. 634,215, dated October 3, 1899.

Application filed April 1, 1899. Serial No. 711,342. (No model.)

To all whom it may concern:

Be it known that I, CHARLES F. NICKERSON, a citizen of the United States, residing in Reading, in the county of Middlesex and State 5 of Massachusetts, have invented a new and useful Improvement in Ventilators, of which the following is a specification.

This invention relates to ventilators, particularly those adapted for application to 10 chimneys, although the device may be used in connection with any structure requiring ventilation, provided the position of the ventilator is such as to allow of the passage through it of a draft of air.

15 The nature of the invention is fully described in detail below, and illustrated in the accompanying drawings, in which—

Figure 1 is a side elevation of my improved ventilator in position on a chimney. Fig. 2 20 is an end view looking toward the direction from which the wind is coming. Fig. 3 is a longitudinal vertical section of the same. Fig. 4 is a horizontal section taken on line X, Fig. 3.

25 Similar letters of reference indicate corresponding parts.

A represents an ordinary chimney.

B is a pipe or flue mounted vertically in the chimney and extending slightly up therefrom. 30 This flue may be of any desired length and may extend as far above the upper end of the chimney as is deemed advisable. The upper end of this flue is provided with a spider C, fixed horizontally therein and centrally perforated, as shown in Fig. 4, to receive the vertical rod or spindle D, which is prevented from dropping by the collar D'. This spindle extends up through the conical horizontal funnel E, the horizontally-set hollow conical deflector F, and the curved cross-piece H, and 35 on its upper end is mounted the hub K' of the rudder or vane K, all of said parts being free to rotate on said spindle.

The horizontal funnel E is cone-shaped, as 45 shown, and its smaller end—that is, the end toward the wind—is provided with a flaring mouth E'. The deflector F is set horizontally within the funnel and is hollow and closed at its smaller end. Its lines are nearly parallel 50 with those of the funnel; but the angle of the sides of the deflector is somewhat more obtuse than that of the sides of the funnel in

order that the annular space between the deflector and funnel may be somewhat larger toward the entering end of the latter. The 55 lower side of the deflector F is provided with an opening F'', from the edges of which a vertical pipe or flue F' extends down over and around the flue B. The lower end of this pipe F' is turned in at f against the flue B sufficiently to prevent any body of air from entering the pipe F' at that point, but not enough to interfere with the free rotation of said pipe F' around the flue B. A vertical partition L is placed within the deflector F near the 60 opening F'' and between it and the smaller end of said deflector for the purpose of preventing the air which passes from the flue and pipe B F' into the deflector from working toward the small end of the latter. The 65 deflector and funnel are soldered together at the point g where the pipe F' extends through the funnel. A pin h extends horizontally through the spindle D between the upper side of the curved cross-piece H and the deflector F and 70 prevents the ventilator from being lifted, said cross-piece being secured at its opposite ends to the inner surface of the deflector. The 75 vane or rudder K is rigidly secured in a vertical position to the upper side of the funnel 80 E and broadens at its end and extends beyond the larger end of the funnel, and said larger end of the funnel extends for a little distance beyond the open end of the deflector F. Suitable braces P extend from opposite 85 sides of the rudder or vane to the funnel.

In operation the vane or rudder K swings the ventilator in line with the direction of the wind and with its smaller end toward the wind. The external air enters the funnel at 90 the flared mouth E', passes in the direction of the arrows between the deflector and the funnel, and thence by the mouth of the deflector out through the larger end of the funnel. The air from the chimney passes up 95 through the flue B and the spider C into the pipe F', and thence through the opening F'' into the deflector F, and thence through the mouth of the deflector into and out through the mouth of the funnel, all as indicated by 100 the arrows. By a well-known natural law the passage of the air through the funnel and by the mouth of the deflector draws and accelerates the passage of the air from the chimney

through the mouth of the deflector, said air from the deflector passing quickly out in order to prevent a vacuum at that point. Moreover, the gradually-narrowing passage between the 5 deflector and funnel tends to accelerate the speed of the external air passing through it, and hence to increase the velocity of the air passing out through the mouth of the deflector.

Having thus fully described my invention, 10 what I claim, and desire to secure by Letters Patent, is—

The herein-described improved ventilator, comprising the flue B; the vertical spindle D extending up from the upper end of said flue; 15 the horizontal cone-shaped funnel E mounted on said spindle and adapted to present its smaller end toward the wind; a rudder or

vane mounted rigidly on the funnel at the larger end thereof, that is, the end opposite that which is presented to the wind; the hollow conical deflector F set horizontally and centrally within said funnel with the pointed end thereof toward the wind and toward the smaller end of the funnel, and being smaller in diameter and shorter in length than said 20 funnel; and the pipe F' rigid with said deflector and extending downward through the lower wall of the funnel and around the flue B, substantially as and for the purpose set forth.

CHARLES F. NICKERSON.
